UNITED STATES PATENT OFFICE

WILLIAM J. KERR, OF SMETHPORT, PENNSYLVANIA

TOY WIND-WHEEL

Application filed June 4, 1932. Serial No. 615,430.

The invention relates to toy wind-wheels of the type in which the wheel is carried by an elongated handle or stick. The wind-wheels of such toys are usually formed from very light celluloid or the like and when a number of the toys are packed for shipment in a single box, carton or the like, there is danger of the handles of some injuring the wind-wheels of others. It is the principal object of my invention however to overcome this difficulty by providing a toy in two separate units which may be readily assembled by the retailer, one of the units including the handle while the other includes the wheel. Pluralities of these units may therefore be separately packed and shipped with less danger of injury and said units may be quickly and easily assembled for sale.

Further objects are to provide an exceptionally simple and inexpensive assembly of wind-wheel and hub, to provide simple and inexpensive, yet efficient bearing means for mounting the wheel with as little friction as possible in a cheap toy, and to provide a new and very decorative wind-wheel formed from sheet material.

With the foregoing in view, the invention resides in the novel subject matter herein-after described and claimed, description being accomplished by reference to the accompanying drawing.

Fig. 1 is a front elevation showing a toy constructed in accordance with the invention.

Fig. 2 is an enlarged vertical sectional view on line 2—2 of Fig. 1.

Fig. 3 is a vertical transverse sectional view on line 3—3 of Fig. 2.

Fig. 4 is a perspective view of a washer forming part of the bearing means.

Fig. 5 is a front elevation showing a different form of the invention.

Fig. 6 is a vertical section on line 6—6 of Fig. 5.

Fig. 7 is an elevation of the two attached sheets of which the wind-wheels of Fig. 5 are formed.

Fig. 8 is a sectional view on line 8—8 of Fig. 7.

Preferred constructions have been shown

and will be specifically described, with the understanding however, that within the scope of the invention as claimed, variations may be made.

The numeral 5 denotes a wheel hub preferably formed from a single piece of wood, said hub being of longitudinally stepped form, providing it with a large end 6, with a small end 7, with a large shoulder 8 and with a small shoulder 9. 10 denotes a thin disk of celluloid or the like from which the wind-wheel is formed, said sheet being slit and bent to provide wind vanes 11 whose ends 12 are overlapped. Disk 10 is formed with a central opening 13 through which the hub 5 passes, said disk lying against the shoulder 8. The overlapped vane ends 12 are formed with aligned openings 13' through which the small end 7 of the hub passes, and for holding these ends substantially against the shoulder 9, a metal sleeve 14 is forced frictionally onto the aforesaid hub end 7. If desired, a smaller wind-wheel 15 may be disposed in advance of the main wheel, being spaced forwardly from the latter sufficiently to clear the same. To so space the two wheels, the small end 7 of the hub 5 is preferably made of sufficient length to accomplish this end. The wheel 15 may contact lightly with the front extremity of the hub end 7 and may be rotatably mounted on a nail 16 driven into said hub end 7. When the extra wheel 15 is employed, it will be observed that the metal sleeve 14 will prevent splitting of the hub 5 when driving the nail 16 into the latter.

The hub 5 is formed with a cylindrical socket 17 which is disposed centrally and opens through the rear end of said hub. Receivable snugly in this socket, is a plug 18 which is rotatably mounted on the front portion of a shaft 19, this shaft being rigidly carried by an elongated handle 20. As manufactured, the parts 18, 19 and 20 and the bearing means for the former, constitute one unit of the toy, while the hub 5 and the wind-wheel or wheels carried thereby, constitute the other unit. These units may be shipped separately in numbers and may be quickly and easily assembled for sale, sim-

ply by tightly forcing the plug 18 of the one unit into the socket 17 of the other unit. By preference, the plug 18 is of hexagonal or similar form in transverse section, providing it with a plurality of longitudinal ridges 21 which tightly engage the wall of the cylindrical socket 17 when forcing said plug into said socket. The plug 18 may well be of such size as to cause the ridges 21 to form grooves in the socket wall when plug and hub are forced together, thereby establishing a tenacious connection between the two.

The shaft 19 is provided with a pointed front end 22 and with an outstanding annular flange 23, the latter being between the ends of said shaft. The plug 18 is in the form of a metal sleeve receiving the front portion of the shaft 19, said sleeve having a closed, preferably conical front end forming a bearing socket or center 24 engaging the pointed shaft end 22. A washer 25 loosely surrounds the shaft 19 and lies loosely against the rear side of the flange 23, and flanges or tongues 26 are bent inwardly from the rear end of the sleeve or plug 18, said flanges or tongues engaging the rear side of said washer. The plug or sleeve 18, washer 25 and shaft 19 are thus held properly assembled, and said plug or sleeve may rotate freely upon said shaft.

In Figs. 5 and 6, I disclose a hub 5^a mounted upon a handle stick 20^a by means of a bearing structure 27 which may be considered as identical with that above described. The hub 5^a is provided with any desired number of radial arms 28, and each of these arms, as well as the front end of the hub 5^a, carries a wind-wheel 29.

Each of the wind-wheels 29 is composed of two superposed sheets 30—31, glued or otherwise secured together and radially split as at 32, so that the corners may be folded into overlapping relation with each other and so held by a pivot pin 33. The sheet 30 is preferably of thin celluloid or the like of an attractive color or colors, said sheet being preferably imperforate, with the exception of openings 34 and 34^a to receive the pivot pin. The sheet 31 contrasts in appearance with the sheet 30 preferably by being a different color or colors therefrom, and this sheet 31 is provided with various openings through which parts of the sheet 30 can be seen. Obviously, these openings may be of any desired shapes, sizes and locations, but for illustrative purposes, I have shown each quarter of the sheet 31 formed with an arcuate slot 35 and with a plurality of circular holes 36. By providing the apertured sheet 31 secured upon the other sheet 30, the two sheets being of contrasting appearance, very pleasing results are obtained. The sheet 31 may be of thin paper, tin-foil or any other desired material.

From the foregoing, it will be seen that I have provided a new and advantageous structure in which the toy is formed of two separate units with the benefits above defined; that a new and improved assemblage of hub and wind-wheel has been produced, that a novel and advantageous bearing has been provided to permit rotation of the wheel with little friction, and that a very attractive wind-wheel has been produced. On account of the excellent results obtainable from the details disclosed, they are preferably followed. However, within the scope of the invention as claimed, variations may be made.

I claim:

1. A toy composed of two separate units; one of said units comprising a wind-wheel having a hub whose rear end is provided with a central socket; the other of said units comprising a handle, a plug readily insertible forwardly into and of a size to be frictionally held in the aforesaid socket, and means rotatably mounting said plug on said handle.

2. A toy composed of two separate units; one of said units comprising a wind-wheel having a hub whose rear end is provided with a central cylindrical socket; the other of said units comprising a handle, a plug readily insertible forwardly into the aforesaid socket, said plug being flat-sided to provide it with longitudinal ridges at the junc- tures of its flat sides and being of a size to cause tight frictional engagement between said ridges and the socket side wall, and means rotatably mounting said plug on said handle.

3. A toy comprising a rotatably mounted hub of longitudinally stepped form providing it with a large and a small end, and with a large and a small shoulder, a wheel-forming disk lying against said large shoulder and having an opening through which said hub passes, said disk being slit and bent to provide vanes whose ends overlap, said overlapped vane ends having openings receiving the small end of said hub, and means holding said vane ends upon said small hub end.

4. A toy comprising a rotatably mounted hub of longitudinally stepped form providing it with a large and a small end, and with a large and a small shoulder, a wheel-forming disk lying against said large shoulder and having an opening through which said hub passes, said disk being slit and bent to provide vanes whose ends overlap, said overlapped vane ends having openings receiving the small end of said hub, and a sleeve frictionally surrounding said small end of said hub and holding said vane ends thereon.

5. A wind-wheel mounting comprising a handle, a shaft projecting rigidly there-

from, said shaft having a pointed front end and an outstanding annular flange between its ends, a washer loosely surrounding said shaft and lying loosely against the rear side 5 of said flange, a wheel independent of said washer, and a sleeve carrying said wheel and receiving the front portion of said shaft, said sleeve having a closed front end formed with a bearing socket engaging said 10 pointed front end of said sleeve, said washer being received within the rear end of said sleeve, said rear end of the sleeve having inwardly bent portions engaging the rear side of said washer.

15 6. In a toy wind-wheel, a flexible sheet radially slit and having corner portions folded substantially upon themselves to form wind vanes, and another sheet contrasting in color to the first mentioned sheet 20 and similarly slit and folded, said other sheet being secured against one side of said first named sheet, one of said sheets having various openings through which portions of the other sheet are visible.

25 7. A toy composed of two separate units; one of said units comprising a hub, and a flexible sheet slit radially and having corner portions folded substantially upon themselves, said sheet and hub being connected 30 to form a wind wheel, said hub being provided with a central socket having an open rear end; the other of said units comprising a handle stick, a pin projecting laterally from said handle stick, and a tubular plug surrounding and rotatably mounted on said pin, said tubular plug being of a size for forward insertion into and snug reception 35 in said socket.

40 In testimony whereof I affix my signature.

WILLIAM J. KERR.
